UNITED STATES PATENT OFFICE.

FRIEDRICH AUGUST ANTONI, OF COLOGNE, GERMANY, ASSIGNOR TO RESOPAN-
GESELLSCHAFT M. B. H., OF COLOGNE, GERMANY.

MAP-HOLDING AND READING APPARATUS.

1,216,393.

Specification of Letters Patent.

Patented Feb. 20, 1917.

Application filed August 8, 1916. Serial No. 113,826.

To all whom it may concern:

Be it known that I, FRIEDRICH AUGUST ANTONI, subject of the King of Prussia, German Emperor, residing at Cologne, in the Province of the Rhine, Germany, have invented certain new and useful Improvements in Map-Holding and Reading Apparatus, of which the following is a specification, reference being had therein to the accompanying drawing.

This invention relates to certain new and useful improvements in map holding and reading apparatus.

Map-pockets as heretofore constructed have been found objectionable because the maps, especially in bad weather, soon become worn and are injured by being repeatedly taken out, handled, and bent around, thus rendering an exact setting practically impossible.

The present invention has for its main object to obviate the objections hitherto existing, and to provide a simple and efficient means whereby maps, plans and the like may be supported and readily placed in position for reading, without danger of injury thereto.

Other objects and advantages of the invention will hereinafter appear and the novel features thereof will be particularly pointed out in the appended claim.

The invention is clearly illustrated in the accompanying drawing, which with the characters of reference indicated thereon, form a part of this specification, and in which—

Figure 1 is a face view with portions broken away.

Fig. 2 is an edge view thereof looking in the direction of the arrows in Fig. 1.

Like characters of reference indicate like parts in the different views.

In the drawing *a a* designate two pairs of axles suitably mounted in the frame or support, and upon each axle is mounted to slide endwise thereof a roller *b c*. Upon each pair of rollers is a band, cut out of a map, for instance, and rolled thereon in such manner that each band may be rolled off from the one roller and rolled up on the

other, an operation rendered possible by the turning of one or the other of the axles of each pair, each band being wound independently of the other. The pair of rollers are adapted to be shifted from the right to the left, and vice versa.

Now, supposing the band with the sections 1, 3 and 5 is rolled up on the rollers *b*, and the band with the sections 2, 4 and 6 on the rollers *c*, the bands will be side by side with the sections 1 and 2 side by side. If now a road across the two bands lying side by side is followed and the border or outer edge of the section 2 is reached the rollers *b* must be shifted to the right and the rollers *c* to the left and the band on the rollers *b* rolled up until its section 3 comes aside the section 2. In this way the bands may be, at will, placed side by side, and a road, as indicated at *m n*, may be followed across the whole map without it being necessary to take the whole map out of the frame.

The bands may be rolled in either direction to bring the right hand or the left hand edges thereof side by side, according to circumstances. When not in use, one band may be placed behind the other, out of the way, and the front band only may be used, until it becomes necessary to bring the other band into operative position to continue the road beyond the edge of the one band.

It is to be understood that the map is cut longitudinally into two parts to form the two bands.

What is claimed as new is:—

A map-holding and reading apparatus, comprising a plurality of pairs of rollers for supporting map sections in the form of bands, said rollers being arranged with the different pairs in different parallel planes, and each pair adapted to be shifted endwise from right to left, or vice versa, independently of the other pair.

In testimony whereof I affix my signature in presence of two witnesses.

FRIEDRICH AUGUST ANTONI.

Witnesses:

OTTO SCHMIDT,
J. BROIDT.
